(57) **CLAIM**

The ornamental design of a container with multiple handles as shown and described.

DESCRIPTION

FIG. 1 is a front right side perspective view of a container with multiple handles;

FIG. 2 is a front elevation view thereof;

FIG. 3 is a back elevation view thereof;

FIG. 4 is a top plan view thereof;

FIG. 5 is a bottom plan view thereof;

FIG. 6 is a right side view thereof; and,

FIG. 7 is a left side view thereof.

The broken lines are for the purpose of illustrating portions of the container with multiple handles that form no part of the claimed design.
